US00D880513S

(12) **United States Design Patent** (10) Patent No.: US D880,513 S
Wang et al. (45) Date of Patent: ** Apr. 7, 2020

- (54) **DISPLAY SCREEN WITH GRAPHICAL USER INTERFACE**

(71) Applicant: **DELTA ELECTRONICS, INC.**,
Taoyuan (TW)

(72) Inventors: **Yi-An Wang**, Taoyuan (TW); **Ya-Fan
Chou**, Taoyuan (TW); **Sih-Yu Chen**,
Taoyuan (TW); **Chun-Chieh Hsu**,
Taoyuan (TW)

(73) Assignee: **DELTA ELECTRONICS, INC.**,
Taoyuan (TW)

(**) Term: **15 Years**

(21) Appl. No.: 29/663,767

(22) Filed: Sep. 19, 2018

(30) **Foreign Application Priority Data**

Jul. 26, 2018 (TW) 107304305

(51) LOC (12) Cl. 14-04

(52) U.S. Cl.

USPC D14/486

(58) Field of Classification Search

See application file for complete search history.

(57) **CLAIM**

The ornamental design for a display screen with graphical user interface, as shown and described.

DESCRIPTION

The single FIGURE is a front view of a display screen with graphical user interface showing our new design. The dash-dot broken line showing of the display screen forms no part of the claimed design. The broken lines showing of portions of the graphical user interface form no part of the claimed design.

1 Claim, 1 Drawing Sheet
